UNITED STATES PATENT OFFICE.

ARTHUR A. BEACH, OF GLENDALE, CALIFORNIA.

SCREW-DRIVING DEVICE.

Application filed April 24, 1924. Serial No. 708,797.

To all whom it may concern:

Be it known that ARTHUR A. BEACH, citizen of the United States, residing at Glendale, in the county of Los Angeles and State of California, has invented certain new and useful Improvements in a Screw-Driving Device, of which the following is a specification.

This invention relates to an improvement in tool holders constructed primarily with a view to permitting the convenient operation of various tools in places and under conditions in which the ordinary tool holder would be of little service.

The invention is directed to a tool holder of comparatively compact form arranged to be supported for operation under ordinarily adverse conditions, the construction providing for convenient operation of the tool in either direction and for applying pressure to the tool during operation if the nature of the tool requires such pressure.

The invention is illustrated in the accompanying drawing, in which:

Fig. 1 is a view in side elevation showing the tool with the parts in operative relation.

Fig. 2 is an edge view of the same.

Fig. 3 is a longitudinal section through the operating handle.

Fig. 4 is a section on line 4-4 of Fig. 3.

Fig. 5 is a partial plan of the handle showing the latch means, whereby the same may be connected to or disconnected from the supporting means.

The improved tool holder comprises a frame including a cylindrical member 1, and an offset curved member 2 at one end of the cylindrical member, the curved member terminating in a bearing portion 3 at right angles to and spaced beyond one end of the cylindrical member. An operating shaft 4 is rotatably supported in the cylindrical member 1 and beyond one end of said member is formed with a helical groove 5, in which is seated a pin 6 removably secured in an operating handle 7. Thus by reciprocation of the handle, the operating shaft 4 is caused to revolve in the cylindrical bearing member 1. The shaft 4 extends beyond the opposite end of the bearing member 1 and is loosely provided with a bevel gear 8, and between the bevel gear 8 and the end of the frame the shaft 4 is rigidly provided with a ratchet wheel 9.

A double ended pawl 10 is carried by the bevel gear 8, and the position of this pawl

relative to the ratchet determines the direction of rotation of the bevel gear, as will be obvious.

A tool shaft 11 is rotatably mounted in the bearing portion 3 of the curved portion of the frame, and this tool shaft carries a bevel gear 12 normally in cooperation with the bevel gear 8, so that in the operation of the bevel gear 8, the shaft 11 is rotated. The free end of the shaft 11 is provided with a socket 13 for the reception of any desired type of tool, here indicated as a screw driver 14, a set screw 15 serving to removably secure the tools within the socket.

A supporting and pressure means is provided for the holder proper, comprising a threaded shaft 16 having at one end a bearing disc 17 connected to the shaft by a universal joint 18, and cooperating at the opposite end with a threaded sleeve 19, having a terminal disc 20 for convenient manipulation of the sleeve, from which disc projects a bearing stud or point 21. A handle member 22 is pivotally connected at 23 on the frame of the holder, the point of pivotal connection being in line with the shaft 11. This handle member projects in line with and terminates adjacent the operating handle 7, the opposite end of the handle member slidably embracing the threaded shaft 16 and being provided with a latch 24, whereby the handle member may be fixed to the shaft 16 at will and at any convenient point in its length. The operative end of the latch cooperates with the threads, or may be withdrawn to permit a free sliding connection between the handle member 22 and the shaft 16.

In operation, particularly in places where the ordinary tool holder could not be used, the improved tool holder is positioned by adjusting the holding member to cause the point 21 and disc 17 to bear against opposite parts of a fixture to support the tool holder for operation. The handle member 22 is then connected to the shaft 16, so that under pressure on the handle end of the handle member, the shaft 11, that is, the tool holder proper, is advanced towards its work. The appropriate tool being placed in the socket 13, the handle 7 is reciprocated, and if the pawl 10 is properly positioned, the tool 14 will be operated to the end desired. Obviously, the shaft 4 is rotarily reciprocated in the movements of the handle 7, and it is apparent therefore that the bevel

gear 8 may be positively driven in either direction at will through a proper setting of the pawl 10. Thus, for example, with the use of a screw driver tool, a screw may be applied or withdrawn.

Claims:

1. A tool including a curved frame having a cylindrical member projecting therefrom, a tool shaft rotatably supported in the curved frame at right angles to the cylindrical member, a tool socket carried by one end of said tool shaft, an operating shaft mounted in the cylindrical member, a handle for operating said shaft, cooperating bevel gears on the operating shaft and tool shaft, to drive the latter in the operation of the former, a supporting means including a threaded shaft terminally formed to permit said shaft to be rigidly held between spaced supports, and a handle member pivotally connected with the curved frame and adjustable longitudinally of the threaded shaft.
2. A tool including a curved frame having a cylindrical member projecting therefrom, a tool shaft rotatably supported in the curved frame at right angles to the cylindrical member, a tool socket carried by one end of said tool shaft, an operating shaft mounted in the cylindrical member, a handle for operating said shaft, cooperating bevel gears on the operating shaft and tool

shaft, to drive the latter in the operation of the former, a supporting means including a threaded shaft terminally formed to permit said shaft to be rigidly held between spaced supports, and a handle member pivotally connected with the curved frame in line with the tool shaft and adjustable longitudinally of the threaded shaft.

3. A tool including a curved frame having a cylindrical member projecting therefrom, a tool shaft rotatably supported in the curved frame at right angles to the cylindrical member, a tool socket carried by one end of said tool shaft, an operating shaft mounted in the cylindrical member, a handle for operating said shaft, cooperating bevel gears on the operating shaft and tool shaft, to drive the latter in the operation of the former; a supporting means including a threaded shaft terminally formed to permit said shaft to be rigidly held between spaced supports, a handle member pivotally connected with the curved frame in line with the tool shaft and adjustable longitudinally of the threaded shaft.

In testimony whereof I affix my signature.

ARTHUR A. BEACH.
